Joshua Gordon Lippincott, New York, N. Y., assignor to Eberhard Faber Corporation, Brooklyn, N. Y., a corporation of Delaware

Application April 17, 1946, Serial No. 128,679

Term of patent 14 years

(Cl. D74—1)

To all whom it may concern:

Be it known that I, Joshua Gordon Lippincott, a citizen of the United States, residing at New York city, in the county of New York and State of New York, have invented a new, original, and ornamental Design for a Cap for a Fountain Pen or Similar Article, of which the following is a specification, reference being had to the accompanying drawing, forming part thereof.

Fig. 1 is a perspective view;

Fig. 2 is a side elevational view; and

Fig. 3 is a front elevational view of a cap for a fountain pen or similar article, showing my new design.

I claim:

The ornamental design for a cap for a fountain pen or similar article, as shown.

JOSHUA GORDON LIPPINCOTT.
